Inventor.

Ray L. Carter.

By Harry De Wallace
Attorney

UNITED STATES PATENT OFFICE.

RAY L. CARTER, OF SYRACUSE, NEW YORK.

HINGE-RECESS GAUGE.

Application filed June 26, 1924. Serial No. 722,548.

To all whom it may concern:

Be it known that I, RAY L. CARTER, a citizen of the United States, residing at Syracuse, in the county of Onondaga and State of New York, have invented certain new and useful Improvements in Hinge-Recess Gauges, of which the following is a specification.

This invention relates to gauges, designed for use by carpenters, for accurately locating and gaging and cutting the recesses or sockets in which the leaves of door-butts or hinges may be disposed.

The primary object of this invention is to provide a hinge recess gauge or templet, which may be readily applied to door frames, wherein the jambs and lintels are correspondingly rabbeted for providing solid, instead of removable, abutments for stopping and supporting the doors when they are closed. A further object is to provide a templet of the class, which is especially adapted for supporting and guiding a power-driven routing machine while the recesses are being formed. And a further object is to provide a recess gauge composed of similar sections or units, one for each hinge, wherein each section is equipped with adjustable means for laying out hinge recesses of different lengths, breadths and depths; the said sections being arranged for mounting upon a common guide-rod, which is normally positioned beyond and clear of the door and frame during the gaging and routing operations.

A particular object is to improve and simplify the devices shown and described in my pending application, Serial No. 670,026, filed October 22, 1923.

I attain these objects by the means set forth in the detailed description which follows, and as illustrated by the accompanying drawings, in which—

Figure 1 is a broken vertical section of a door-frame, to which my sectional recess gauge is applied. Fig. 2 is a horizontal section, taken on line 2—2 of Fig. 1, and a top-plan view of the gauge. Fig. 3 is a broken edge view of a door; showing the lower-most unit of the gauge of Fig. 1 inverted and applied to the top portion of the door. Fig. 4 is a broken front side elevation of the door, and an edge view of the gauge of Fig. 3. Fig. 5 is a rear face view of one of the sections of the gauge. Fig. 6 is a broken rear face view of the door, with

the gauge attached; showing a motor-driven router in the act of cutting the top-hinge recess. Fig. 7 is a detached view of the tubular clamp. And Fig. 8 is respectively a front face and an edge view of one of the slotted plates by which the height of the recess is gaged.

In the drawings, 2 represents one of the jambs of a door-frame, 2' the lintel, and 2^a the corresponding rabbeted portions of the jamb and lintel which receive the lateral and top margins of the door 3.

My sectional hinge recess gauge consists of two or more similar normally open frames or members, as A and B, each of which is provided with one plain straight lateral edge *a*, which parallel the solid abutment 2^b of the jamb, as well as the corresponding face 3' of the door 3, as shown in Figs. 1, 2 and 3. The opposite edge of the frame (A or B) is provided with laterally projecting spaced integral guide-lugs 4, having alining perforations to receive a common guide-rod 5, upon which the several frames or members may be adjustably mounted. The frames A—B are held in place on the rod 5 by means of similar novel clamping devices, which consist of tubes 6, whose length equals the space between the lugs 4, and which slidably receive the rod 5; the top ends of said tubes being split, as at 6'. The split ends of the tubes 6 telescope perforated blocks, as 6^a, the latter being provided with transverse threaded holes into which is screwed set-screw 6^b, whose inner ends engage one jaw of the tubes and compress said jaw against the rod 5, for frictionally holding the gauge parts in the adjusted positions. The lugs 4 are also provided with transverse threaded holes that receive adjusting screws 4', which pass beneath the rod 5 and their free ends overlie the bottom face of the frame, as shown in Figs. 1, 2, 3 and 5. The screws 4' are employed for adjusting the frames A—B, when the latter are applied to the jamb 2, as shown in Fig. 1, wherein the said screws are in engagement with the outer edge of the jamb, for gaging the breadth of the recesses *a*—*b*. The rabbeted portions 2^a are usually about two inches in breadth, for accommodating doors that are two inches thick. When doors of less thickness are to be hung in the rabbeted jambs, the frames A and B are adjustably set, by means of the screws 4' (see

Fig. 1), the required distance from the abutment 2^b , and the vacant space, indicated at 2^c in Fig. 1, is usually fitted with a liner or strip 2^d , for closing the said gap. When heavier doors, whose thickness equals the rabbets 2^a are to be hung, all the frames of the recess gauge are adjusted inwardly, by reversing the screws $4'$ until the plain edges a of the frames substantially abut 10 against the ledge 2^b , as shown by dotted lines in Fig. 1.

The frames A—B preferably comprise similar parallel side rails 7 and $7'$, which are spaced to a slightly greater extent than 15 the breadth of the leaves of the largest hinges in common use, by means of similar relatively thin webs 7^a , which are spaced to provide relatively long openings 7^b (see Fig. 5) that register with the hinge recesses, and 20 through which a routing or other recessing tool 12 may be inserted, as shown in Figs. 5 and 6. At the opposite ends of the rails $7—7'$, the webs 7^a are extended for forming lugs 7^c , which are perforated, and through 25 which brads or small nails 7^d may be driven, for temporarily securing the frames to a jamb or door, while the routing of the recesses is being effected, as shown in Figs. 2, 4 and 6. The vertical dimensions of 30 the recesses for hinges of different length may be varied or regulated, by means of similar guide-plates 8 , which are slidably mounted on the top faces of the webs 7^a , between the rails $7—7'$, as shown in Figs. 35 1, 2 and 3; the said plates being adjustably held in place by screws $8'$, which pass through slots 8^a of the plates and are threaded into the said webs. The outer ends of 40 the plates 8 are formed with similar heads 8^b , which play in longitudinal slots of the webs, as at 7^e , and one head of each pair of plates is bored out (see Figs. 1, 3, 5 and 8) to receive a short rod 9 , which constitutes one member of an adjustable limit- 45 gauge, the other member of which comprises a tube $9'$, which is slidable on the rod, for varying the distance between the top hinge and the bottom surface of the lintel $2'$, as best seen in Fig. 1. For this purpose, the 50 rods 9 are provided with single perforations, as 9^a , to receive cotter or other pins 9^b , which may be inserted through either one of several perforations 9^c formed in the tube $9'$ (see Fig. 4). The free end of 55 each tube $9'$ is fitted with a laterally projecting arm 9^d , the said arm being relatively thin for gaging the usual narrow clearance between the top edge of the door 3 and the lintel $2'$, as shown by dotted lines in Figs. 1 and 3. The lowermost plate 8 of the frame B is also provided with similar limit-gauge parts (see Fig. 1), which depend idly, while the templet is being employed for locating and forming the recesses 60 of the jamb 2 . When the operator is ready

to cut the recesses in the door 3 , he releases the templet from the jamb and inverts it, for positioning the frame B near the top end of the door, as shown in Figs. 70 3 and 4. This inversion of the templet disposes the guide-rod 5 at the left side of the door, thus reversing the order of the recesses 3^a of the door, as compared with the recesses $a—b$ of the jamb. The frame B is preferably held with its plain edge a (rail 7) flush with the outer face of the door, by a pair of stops 10 , which are pivoted to the rail 7 by screws $10'$, and which may be swung downwardly for overlapping the door, as best seen in Fig. 4. The stops 10 are swung into alignment with the rails 7 when the templet is applied to the jamb (see Fig. 1), and being preferably relatively thin, serve to slightly space the inner face of the door from the abutment 2^b , or 85 from the liner 2^d , as shown in Fig. 1, for preventing chafing of the door. Upon reversing the templet for mortising the door 3 , the arm 9^e of frame B is hooked over the top end of the door, as shown in Figs. 90 3, 4 and 6. By this provision and arrangement, the several recesses of the door will be suitably located, for providing the usual clearance at the top of the door, when the latter is finally hung. 95

The routing tool 12 is driven by the shaft $12'$ of a motor 13 , which is enclosed in a threaded casing $13'$, the latter being screwed into a hollow support 14 , for adjusting the tool 12 relatively to the frame B, for regulating the depth of the recess 3^a . The bottom of the holder 13 is preferably flat and smooth, and is adapted to slide over the top faces of the rails $7—7'$ during the routing work. The tool 12 extends below a cylindrical guide 13^b , which is attached to the motor shell $13'$. This guide bears against the inner faces of the rails $7—7'$, and also against the facing ends of the guide-plates 8 , as shown by dotted lines in 110 Fig. 1. By this arrangement of the parts, the recesses are smaller than the clear openings in the frames A—B, as shown by dotted lines in Figs. 1 and 3.

For doors equipped with more than two 115 hinges, plain frames similar to those shown in the drawings, but without the limit gauges 9 , may be adjustably mounted on the rod 5 between the frames A and B, for gaging the additional recesses.

From the foregoing, it will be understood that the recess gauge of my pending application, is not adapted for gaging hinge recesses of rabbeted door jambs, as herein shown and described. The present invention is designed to perform the same functions as the former device, but in a simpler manner, with fewer parts, and with greater convenience, accuracy and economy. 125

Obviously, with a few slight changes in 130

the construction and arrangement of some of the parts, the present invention may be adapted for gaging many different kinds of work, and I therefore do not limit its use 5 to hinge recesses.

Having thus described my invention, what I claim, is—

1. In a device for gaging recesses of doors and rabbeted door-frames, an open 10 body having one plain lateral edge adapted to engage an abutment of the frame, the opposite edge of said body being provided with alining perforated lugs, a guide-rod passing through said lugs, a sleeve mounted 15 on said rod between said lugs, and means for compressing the sleeve against the rod for rigidly holding the body in place.

2. In a device for gaging hinge recesses, an open frame comprising parallel rails 20 spaced by lateral integral webs, the said webs being spaced longitudinally for providing a relatively long fixed opening affording play for and for guiding a routing tool, one of said rails being plain, the other rail being 25 provided with alining perforated lugs, a tube partially split disposed between said lugs, a guide-rod passing through said lugs and said tube, and means for clamping the split portion of said tube to said rod.

3. In a device for gaging hinge recesses, an open frame having one plain lateral edge, the opposite lateral edge being formed with spaced perforated lugs, a guide-rod passing 30 through said lugs, means interposed between said lugs for preventing accidental movement of said frame on said rod, plates mounted adjacent the opening in said frame and being movable towards and from each other for gaging the lengths of hinge recesses, and means for holding said plates in 35 the adjusted positions.

4. In a device for gaging hinge recesses, a frame comprising spaced parallel rails 45 connected at their opposite ends by similar sunken webs, slotted plates adjustably mounted on said webs between said rails adapted to be moved towards and from each other for gaging the height of the recesses, alining perforated lugs formed on one of 50 said rails, a guide-rod passing through said lugs and clamping means disposed between said lugs and engaging said rod for holding said frame in various adjusted positions.

5. In a device for gaging hinge recesses 55 of doors and door-frames, a single guide-rod, an open body having one plain edge adapted to engage an abutment of the door-frame, the opposite edge of the body pivotally and slidably engaging said rod, means for holding 60 the body against slidable and rotatable movements on said rod, means for varying the height of the hinge recesses, and means for spacing the recesses relatively to said abutment.

6. A device for gaging hinge recesses, in- 65

cluding a guide-rod, a plurality of open frames adjustably mounted on said rod, each frame comprising parallel rails connected by spaced webs, one of said rails being plain, the other rail being formed with spaced per- 70 forated lateral extensions through which said guide-rod passes, means carried by said extensions for adjusting said frames laterally relatively to the jamb of a door-frame, and spaced guide-plates slidably mounted on the 75 webs of the frames adapted for increasing and decreasing the openings in said frames.

7. A device for gaging hinge recesses, including a guide-rod, a plurality of similar normally open frames adjustably supported 80 by said guide-rod, said frames comprising spaced side rails that parallel said guide-rod, one of said rails being formed with spaced perforated lugs for slidably receiving said guide-rod, means interposed between said 85 lugs for holding said frames in various adjusted positions on said rod, means carried by said lugs for adjusting said frames laterally relatively to a door frame, and means interposed between said rails for gaging 90 hinge recesses of different lengths.

8. A device for gaging hinge recesses of doors and rabbeted door frames, including a pair of parallel rails connected by spaced webs, means adjustably mounted on said 95 webs for gaging hinge recesses of different lengths, stops carried by one of said rails for positioning said rail flush with one side of a door, the other rail being provided with spaced perforated lugs, a guide rod passing 100 through said lugs, means interposed between said lugs for holding the gauge in various adjusted positions on said rod, and means disposed beneath said webs for gaging the breadths of the hinge recesses. 105

9. A sectional device for gaging the hinge recesses of doors and their frames, including a single guide-rod, a plurality of normally open members slidably mounted on said rod adapted for gaging several hinge 110 recesses at one operation, means for independently locking and holding said members in various adjusted positions relatively to each other, guide plates mounted on said members and movable towards and from each other across the openings in said members, and means operable at right angles to said guide-rod for adjusting said members laterally.

10. A sectional device for gaging the hinge recesses of doors and their frames, including a single guide-rod, a plurality of normally open members slidably mounted on said rod adapted for gaging several hinge recesses at one operation, means for independently locking said members to said guide-rod, plates for gaging the opposite ends of the recesses mounted upon said members and movable towards and from each other across the openings in said members, means operable be- 130

neath said members for adjusting the members laterally, and extensible means carried by one plate of each member for gaging the distance of the uppermost hinge from the lintel of the door-frame.

11. A device for gaging hinge recesses of rabbeted door frames, including an open frame having one plain lateral edge adapted to engage the abutment of the rabbet, the opposite lateral edge of the frame being provided with spaced perforated guide-portions,

a rod passing through said guide-portions, means carried by said guide-portions for spacing the plain edge of the frame from said abutment for varying the breadth of the recesses, means carried by said plain edge for providing clearance between the door and said abutment, and means interposed between said guide-portions for holding the frame from accidental movement on said rod. ¹⁵

In testimony whereof I affix my signature.

RAY L. CARTER
